HYPERFREQUENCY WIDE-BAND IMPED-
ANCE MATCHING NETWORK

Richard Wallauschek, L'Etang-la-Ville, France

Application June 17, 1949, Serial No. 99,812
In France June 16, 1948

6 Claims. (Cl. 178—44)

1

The present invention relates to an impedance transforming device with a high transformation ratio, adjustable and applicable to a wide frequency band in the hyperfrequency range.

In the hyperfrequency technique, the problem is often encountered of transforming an impedance into another impedance of any value. In practice, special circumstances, associated with each particular case limit the generality of the problem thus stated, and lead to the distinguishing of several types of transformers. Each one of these types is adapted to a certain application or group of applications; new requirements often lead to the design of new types of transformers.

The object of the present invention is a matching network which has been especially designed for application to the case of the matching of two widely different impedances over a wide band of frequencies and with a good efficiency, while providing for certain adjustments whose necessity often arises in the course of the operation of an ultra-high frequency system, as, for example, altering the impedance-transformation ratio or the mean frequency of the frequency band to be transmitted. Such circumstances are frequently encountered when one of the impedances to be matched is that of a built-in part of an electronic tube which is liable to be often replaced; or, alternately, it may be desired to change the operating frequency band without replacing the impedance-matching network.

The invention concerns an impedance transformer particularly well-adapted to these various purposes, and offering the following advantages:

1. A very high impedance transformation ratio, of the order of 5 to 10, for example.
2. A transformation ratio adjustable over a certain transformation range.
3. A wide enough frequency band for any adjustment of its elements.

The realisation of the transformer device is effected by using, either two-conductor lines or wave guides. These two possibilities also exist for the realisation of the aforesaid built-in part inside the tube.

While impedance-matching devices including quarter-wave lines or transmission line sections used as substitutes for inductances or capacitances at high frequencies have long been known, such devices lack flexibility, particularly as concerns their adaptability to alteration of their mean working frequency or their transformation ratio. The object of the present invention is to obviate these drawbacks by using a combination comprising a transformation line whose length is close to a quarter wave-length, associated with three adjustable condensers in a particular arrangement.

2

In accordance with the invention, the matching network comprises, in combination, a transformation line whose length is close to a quarter wave-length and whose characteristic impedance is intermediate between the two impedances to be matched, a series capacity for obtaining a wide compensation of the selectivity and two shunt capacities, one at the input, the other one at the output of the device, whose capacitive reactances are variable and may be adjusted so as to modify the impedance transformation ratio of the whole device.

The respective functions and interactions of the various elements of the device appear from the detailed description which will now be given. This description is made in connection with the appended drawings wherein:

Figure 1 represents an electric diagram of the device;

Figures 2 to 5, inclusive, are diagrams, in the complex plane, of the impedances at the various points of the hyperfrequency chain.

Figure 6 shows an example of a practical embodiment of the device of the invention.

In the case in which both impedances to be matched are those of coaxial lines, said case being chosen for description purposes, the device is shown schematically on Figure 1. The output line, with a characteristic impedance Z_2 , is assumed to be normal to the plane of the figure. For a better explanation (in practice the input and output lines are often perpendicular to each other), the other impedance Z_1 is represented by a line assumed to be terminated by its characteristic impedance Z_1 . The two lines are connected by a line of length L' , and of characteristic impedance Z' . But between Z' and Z_1 , a variable capacity C' is inserted while Z' and Z_2 , as the case may be, are either in direct contact or electrically associated by a capacity large enough to present an impedance which is negligible with respect to Z' . A variable shunt capacity C_1 is further connected at the input to Z_1 and another variable capacity C_2 at the output of Z_2 . There is included in C_2 , the reactance caused by the disturbance due to the passing from Z_2 to Z' , a disturbance which is generally equivalent to a shunt capacity.

The group of values Z' , L' , C' , C_1 , C_2 is selected in such a manner that the matching is established between Z_1 and Z_2 . The matching of two impedances being, in principle, a two-parameter problem, an infinity of such transformations are obtainable with the five parameters shown. This transformation is described in Figure 2 for two different embodiments by using a conventional representation of the impedances in the complex plane.

The image of impedance Z_2 , assumed real, is on the real axis OR of the diagram of Figure 2. The effect of the shunt capacity C_2 is manifested by a displacement along a circle going through the image Z_2 of the real impedance and the origin O, and whose center is on OR. This displacement Z_2P_1 is determined by the value of C_2 . The transformation along Z' is represented by a displacement P_1P_2 on a circle whose center is on OR, the center and the radius being dependent upon the given points Z' and P_1 while the displacement P_1P_2 depends on the length L' . Point P_2 then represents the impedance obtained at the opposite end of said line of length L' . The connecting of C' in series causes the displacement P_2P_3 , the connecting of the capacity C_1 in shunt completes the transformation and

$$p = \frac{(\overline{OZ}_1)^2 + (\overline{OP} \cdot \overline{OP}) - \sqrt{((\overline{OZ}_1)^2 + (\overline{OP} \cdot \overline{OP}))^2 - (\overline{OZ}_1)^2(\overline{OP} + \overline{OP})^2}}{(\overline{OZ}_1)(\overline{OP} + \overline{OP})}$$

must lead to the point representing Z_1 , by a displacement P_3Z_1 along a circle passing through O and Z_1 and whose center is on OR. A second realization, similar to this transformation is represented in broken lines, also on Figure 2.

The excess number of parameters available gives the possibility of also meeting the other requirements imposed on this matching network. For constructional reasons, a solution is desired in which Z' and L' are well matched but fixed values, and the variation of the transformation ratio will be effected solely by modifying the capacities C_1 , C_2 and C' .

For a better distinguishing of the effects of each one of these parameters, assume first $C_1 = C_2 = 0$. Figure 3 then represents for an average frequency f_0 , the transformation effected by a transformation line Z' , of a length L' , on a real impedance Z_2 (transformation Z_2P_2), followed by a transformation P_2P_4 caused by a series capacity C' .

For a frequency f_1 , lower than f_0 , the electrical length L' decreases, and, consequently, the transformation due to line Z' is represented (Figure 3), by a smaller displacement Z_2P_2' , while the vertical displacement due to capacity C' increases, which is manifested by a lengthening of $P_2'P_4'$. The reverse takes place for a frequency f_2 higher than f_0 (images P_2'' and P_4'').

It will be seen that a certain compensation of the selectivity exists in the device; it is due to the fact that the sense of the vertical displacement, corresponding to the series capacity, as a function of the frequency, is inverse to that of the component parallel with TT' , the most important one, of the displacement corresponding to the transformation line. The curve P_4'', P_4', P_4''' which is the locus of the end of the vector representing the input impedance to the device, is tangent to the vertical tangent TT' of the transformation circle and asymptotic to the other vertical tangent TT' . With a suitable choice of the impedance Z_1 , the vector representing the transformed impedance at the end of this line does not differ too much from vector OZ_1 at frequencies close to f_0 .

With a smaller capacity C' , one may obtain an exact matching at point Z_1 , for frequency f_0 , but in such a case the pass band becomes smaller (see the dotted curve of Figure 3). In fact, if capacity C' is decreased, to obtain the exact matching for a certain frequency f_0 , it will be seen that point P_4''' must be replaced by P_5''' for the corresponding frequency f_1' , the distance Z_1P_5''' then becomes larger than its initial value Z_1P_4''' .

It amounts to the same thing to say that the transformation coefficient for frequency f_1' has been decreased by the modification of C' . For this reason, in general, the desire for an exact matching, at one frequency will be sacrificed to the obtention of a sufficient matching inside a wide band, even if an exact matching is never effected.

Generally, the transmission quality of the matching network may be characterized by giving the transmission curve, i. e. the curve showing the variations of the transmission coefficient t as a function of frequency:

$$t = \frac{4 \cdot p}{(p+1)^2}$$

with

OP being the vector radius of a point P variable along the curve containing all the points resulting from the transformation in the complex plane of impedances (points P_4 , P_4' , P_4'' , P_4''' , etc. of Figure 3). The transmission range is determined by the range within which the transmission coefficient differs from unity only by a value lower than a limiting value.

Conversely, if one considers impedances Z_1 and Z_2 as given, one finds, for each transformation line whose impedance Z' is lower than

$$\sqrt{Z_1 Z_2}$$

a capacity C' which gives, over a certain frequency range around f_0 an input impedance not too different from Z_1 . The more Z' is lower than

$$\sqrt{Z_1 Z_2}$$

the wider this range is, but the larger the impedance variation is inside this range. The choice of the three values Z' , L' , C' thus defines, for a given impedance Z_2 , the frequency band and the variation of the transmission curve.

Consider now the effect of capacities C_1 and C_2 . Since the electrical distance between these two capacities is approximately a quarter wavelength their effects on the system cancel each other if the ratio of their reactances is approximately equal to the transformation ratio of the transformer. Suppose that $\bar{C}_1$ and $\bar{C}_2$ are such values; Figure 4 shows the diagram of the resulting transformation. An accurate investigation

of the problem shows that the presence of capacities C_1 and C_2 decreases, either by narrowing the band or by making the matching less accurate, the transmission qualities, this decrease being smaller when the capacities are smaller, but it does not involve any qualitative variation of the operation described in Figure 3. The locus of points P_4 shows the same compensation of selectivity about a certain frequency f_0 .

Finally, we shall consider the case of a possible variation of the internal impedance Z_2 , i. e. particularly the case where a tube is changed. Assume first that for an average frequency f_0 and with capacities $\bar{C}_1$, $\bar{C}_2$, which, for an average

adjustment are fairly small and are further in a ratio equal to the transformation ratio, the matching, for an average output impedance Z_2 , be effected according to the transformation Z_2 , P_1 , P_2 , P_3 , Z_1 of Figure 5.

For a higher output impedance $\bar{Z}_2$, the trans-

formation $\bar{Z}_2$, $(\bar{P}_1)$, $(\bar{P}_2)$, $(\bar{P}_3)$, $(\bar{P}_4)$ corresponding to the same values $\bar{C}_1$, $\bar{C}_2$, C' does not give a matching with Z_1 . The matching, however, is obtainable with slightly higher capacities C_1 and C_2 and a slightly smaller capacity C' without having to change the transformation line Z' , L' . This transformation giving the matching of $\bar{Z}_2$ with Z_1 is represented in Figure 5, by the transformation $\bar{Z}_2$, P_1 , P_2 , P_3 , Z_1 for which the capacities C_1 and C_2 are in the same ratio as in the transformation Z_2 , P_1 , P_2 , P_3 , Z_1 , in which there is a compensation of the variations, as a function of the frequency, of the reactances corresponding to C_1 , C_2 respectively.

The capacities C_1 , C_2 thus give the means of matching a certain range of output impedances Z_2 with the input impedance Z_1 for a mean frequency f_0 ; they are given such values that their variations, upon a frequency variation about f_0 , approximately cancel each other. The transformation line is given values Z' and L' , such that for the average output impedance Z_2 , the transmission qualities inside the desired band be optimal. For output impedances different from the mean Z_2 , optimum transmission qualities are obtained by an adjustment of the capacities C_1 , C_2 , C' according to what has already been stated. In this case, the transmission qualities are modified to a certain extent; this modification is smaller when the relative variation of the output impedance is smaller.

Due to the effect of the series capacity C' , the device embodying the invention is better than the simple adapter consisting of a single quarter wave line; it is possible to obtain a sufficient matching over a wider frequency range. Due to the use of capacities C_1 and C_2 , an improvement is obtained as regards the possibility of matching a variable internal impedance within a certain range. It was noted that the two functions of the device are related to each other so that after an adjustment of the capacities C_1 and C_2 , a correction of C' improves the transmission qualities.

Generally, the frequency band passed is related to a proper adjustment of C' , while the most complete power transmission must be sought by adjusting the capacities C_1 and C_2 .

A simple embodiment of the invention, taken by way of non limitative example, is represented in Figure 6. An outer cylindrical conductor A, common to the whole device, contains the inner conductor B, corresponding to the line which has a high characteristic impedance Z_2 and the inner conductor C forms the line with a small characteristic impedance Z_1 . An element D is arranged so as to slide over C, thus forming an extension of adjustable length to the conductor C. The transformation line of intermediate impedance Z' and length L' is represented at E; this element is centered and attached inside A by an insulating support F, which consists of a dielectric with a very low dielectric constant, using as small an amount of dielectric as possible to avoid disturbances. A similar support G centers and attaches element D inside a tube H sliding inside the outer conductor A.

By displacing the assembly DGH, the distance between D and E is varied, which realizes the variable series capacity C' . This latter displacement is effected by means of the rod L, associated with H and sliding inside the slot I provided in the outer conductor A and of the

screw M, screwed in H and sliding inside the slot J.

By adjusting this screw M more or less towards the conductor D the shunt capacity playing the part of C_1 is varied. The similar screw N plays the part of the variable shunt capacity C_2 .

For certain applications, it is convenient to replace one or both capacities by lateral plungers with a capacitive input impedance, to have available, for instance, an outlet which makes it possible to vary a direct current in one of the inner conductors.

I claim:

1. An impedance transformation device operable over a wide frequency band in the hyperfrequency range, for matching a first impedance to a second impedance of widely different value, comprising a transformation line having at least one conductor and a length close to a quarter-wave length of the operating frequency and a characteristic impedance of a value intermediate between those of said first and second impedances and of a value between that equal to and that somewhat lower than the geometric mean of the values of said first and second impedances, and means coupling it between said first and second impedances, said coupling means including an adjustable series capacity in series with the line at one of its ends and two adjustable shunt capacities respectively connected in parallel with the above said first and second impedances, said second impedance being that of a transmission line having one or more conductors and means to adjust a conductor of one of said lines relatively to a corresponding conductor of the other of said lines to constitute said series capacity.
2. An impedance transformation device according to claim 1, wherein the ratio between the reactances of the said shunt capacities is substantially equal to the ratio of the impedances to be matched.
3. An impedance transformation device according to claim 1, wherein the said transformation and transmission lines include also a conductor common to said lines.
4. An impedance transformation device according to claim 3, wherein said lines are of the coaxial type and the said common conductor is the outer conductor.
5. An impedance transformation device according to claim 4, wherein the said first impedance is that of a transmission line of the coaxial type having its outer conductor common with said common conductor.
6. An impedance transformation device according to claim 4, wherein means to adjust the capacity connected in shunt of one or both of the said impedances to be matched and the means to adjust the series capacity are carried on the said outer conductor.
